SANDBLAST NOZZLE

John Allen Heany, New Haven, Conn., assignor
to Heany Industrial Ceramic Corporation,
Rochester, N. Y., a corporation of New York

Application June 29, 1942, Serial No. 448,897

5 Claims. (Cl. 51—11)

This invention relates to nozzles and particularly to nozzles employed for sand blasts.

Among the objects of this invention is to provide a sand blast nozzle wherein air leakage is practically eliminated. Another object is to provide a nozzle in which offsetting or shifting of the air current, thus causing improper alignment and short nozzle life, is prevented. Still another object is to provide means for preventing fracture or distortion of the nozzle due to dropping or whipping at the on-set of the air pressure.

Additional objects pertain to improved means for inserting and removing the nozzle in the hose sheath, for utilizing ceramics in nozzle construction, and for reducing weight to facilitate handling.

Further objects may be apparent on consideration of the following description and the accompanying drawing, in which:

Fig. 1 is a perspective view of the casing-nozzle unit;

Fig. 2 is a section showing the invention as applied to a ceramic nozzle and;

Fig. 3 is a section showing the invention as applied to an all metal nozzle.

Referring to the drawing, Fig. 2 shows one form of my invention in which a ceramic nozzle tube 10 is employed. This tube in appearance is cylindrical in shape but possesses a slight taper of about five-eighths of an inch to the foot, from inlet end 11 to outlet end 12. A straight bore 13 having an inlet flare 14 is formed axially in the tube.

A shell 15 of general cylindrical formation encloses the tube at the side and a portion of the outlet end 12. This shell is preferably of metal to provide the requisite holding strength, and is formed on the external side surface with radially displaced areas 16 to provide a suitable contact surface for the elastic sheath 17. This contact surface may take the form of simple depressions and elevations, of annular ridges or of a screw thread as shown in the drawing, the thread being relatively broad and flat and continuous from end to end of the shell.

The shell is preferably tapered toward the outlet end, as for example one-quarter of an inch to the foot, to insure a tight fit in the sheath 17. Also, the outlet end of the shell is partially closed by an integral head 18 having an axial opening 19 in alignment with the opening of the shell but of lesser diameter so that an internal shoulder 20 is formed by the head within the shell. Within the shell and against the shoulder 20 the 55

nozzle tube 10 is inserted, a suitable cement 21 holding the tube in place. It is pointed out that the shell head opening 19 is of larger diameter than the tube duct 13 so as not to interfere with expansion of the air stream when the nozzle is in use.

The shell head 18 also is flattened on opposite sides 22 to form a wrench nut 23 by means of which the shell may be screwed into and out of the enclosing sheath 17.

The sheath 17 is a covering for the shell made of elastic, resilient or yieldable material common in hose manufacture, and may be an isolated element or, as is more usually the case, 15 may form of a hose or other conduit for conveying air and abrasive to the nozzle.

The uses of the sheath 17 are several. It provides a protection for the nozzle elements which may be of ceramic material, so that these elements are not offset or broken by dropping or 20 whipping of the hose end on the application of air pressure. It maintains an effective seal against air losses at the nozzle junction. It prevents displacement of the nozzle alignment with 25 resultant premature destruction of the nozzle elements.

The shell 10 is screwed into the sheath which, being elastic, yields to the broad screw thread and forms a close binding seal thereover. To 30 prevent accidental withdrawal of the shell and provide a positive bond, a hose clamp 24 is applied to the sheath, this clamp having any of the forms common in this art, as far example curvilinear wires terminating in separable bolted end plates. The action of the clamp is to force 35 sections of the elastic sheath material into the screw groove and insures an effective air seal and bond between shell and sheath.

Fig. 3 discloses a modification of the invention wherein only three nozzle elements are used, the tube 30, the sheath 31 and clamp 32. In this inventive form the tube is of metal or other hard substance, being elongated, as shown, and provided with an axial duct 33 having an outwardly flared inlet 34. Also, the outlet end 35 is formed as a nut as in Figs. 1 and 2. The sheath 31 follows the pattern of sheath 17, and clamp 32 is similar to clamp 24 of Fig. 2.

In using either form of the nozzle disclosed the 50 air current impacts against the flared inlet, the flare tending to center the nozzle tube. Since no washers are used and since the relatively long sheath surface and the clamp provide a perfect seal, there is no leakage on one side or section with a consequent side shifting of the air blast

current and irregular erosion and shorter life of the nozzle. Since the true alignment of nozzle relative to hose is constantly maintained the emitting air current is centrally positioned, making use of the air blast by the operator more efficient.

When the nozzle element is worn out, the head 22 is turned by a wrench to remove the shell and tube and new elements are inserted.

It is apparent that the nozzle tube construction may be varied in form and hence limitations should not be imposed on the nozzle structure other than are required by the scope of the claims hereto appended.

I claim as my invention:

1. A sand blast nozzle comprising a nozzle tube having a central duct terminating in a flared inlet orifice, a casing enclosing the side and a portion of one end of the tube, and a protective sheath covering substantially the entire side area of said casing, said sheath forming a uniform, continuous extension of the nozzle supply conduit.

2. A sand blast nozzle comprising a nozzle tube having a central duct terminating in a flared inlet orifice, a casing enclosing the side and a portion of one end of the tube, an elastic sheath covering substantially the entire side area of said casing, and means for binding the sheath to the casing, said sheath forming a part of the nozzle supply conduit.

3. A sand blast nozzle unit comprising an elongated nozzle tube having inlet and outlet ends and having an axial duct terminating at the inlet end in a conical flare, a casing enclosing the side and a portion of the outlet end of said nozzle tube

whereby a retaining shoulder is formed by the casing at the outlet end, means for holding the nozzle tube within the casing, and an elastic sheath enclosing the side of the casing, the outer wall of said casing and the outer wall of said tube tapering toward the outlet end of the tube and the sheath forming part of the nozzle conduit.

4. A sand blast nozzle unit comprising an elongated nozzle tube having inlet and outlet ends and having an axial duct terminating at the inlet end in a conical flare, a casing enclosing the side and a portion of the outlet end of said nozzle tube

whereby a retaining shoulder is formed by the casing at the outlet end, means for holding the nozzle tube within the casing, and an elastic sheath enclosing the side of the casing, the outer wall of said casing and the outer wall of said tube tapering toward the outlet end of the tube and the sheath forming part of the nozzle conduit.

5. A sand blast nozzle comprising an elongated nozzle tube having inlet and outlet ends and having an axial duct terminating at the inlet end in a conical flare, a casing enclosing the side and a portion of the outlet end of said nozzle tube

whereby a retaining shoulder is formed by the casing at the outlet end, means for holding the nozzle tube within the casing, and an elastic sheath enclosing the side of the casing, the outer wall of said casing and the outer wall of said tube tapering toward the outlet end of the tube and the sheath forming part of the nozzle conduit.

6. A sand blast nozzle comprising an externally ridged metal casing, an outlet element integral with said casing, said element having a central opening of a diameter less than the internal diameter of said casing whereby a shoulder is formed at the casing outlet end, a nozzle tube secured within said casing, the outlet end thereof

engaging the casing shoulder, said tube having an axial duct of lesser diameter than that of the outlet element, an elastic sheath covering substantially all of said shell, and means for binding the sheath to the shell, said sheath forming a part of the nozzle conduit.

JOHN ALLEN HEANY.
